CLAIM

The ornamental design for a magnetic shotgun shell strip, as shown and described.

DESCRIPTION

FIG. 1 is a perspective view of the magnetic shotgun shell strip, showing the new design;

FIG. 2 is a front elevational view of the magnetic shotgun shell strip thereof;

FIG. 3 is a rear elevational view of the magnetic shotgun shell strip thereof;

FIG. 4 is a left side elevational view of the magnetic shotgun shell strip thereof;

FIG. 5 is a right side elevational view of the magnetic shotgun shell strip thereof;

FIG. 6 is a top plan view of the magnetic shotgun shell strip thereof;

FIG. 7 is a bottom plan view of the magnetic shotgun shell strip thereof; and,

FIG. 8 is an environmental perspective view of the magnetic shotgun shell strip thereof.

The broken lines in the drawings depict portions of the magnetic shotgun shell strip and form no part of the claimed design; additional broken lines in FIG. 8 depict environment and form no part of the claimed design.

1 Claim, 4 Drawing Sheets
